UNITED STATES PATENT OFFICE.

THEODORE HAUSER, OF CASSOPOLIS, MICHIGAN.

TIE FOR UPHOLSTERY SPRINGS.

Application filed August 30, 1923. Serial No. 660,119.

To all whom it may concern:

Be it known that I, THEODORE HAUSER, a citizen of the United States, residing at Cassopolis, in the county of Cass and State of Michigan, have invented certain new and useful Improvements in Ties for Upholstery Springs, of which the following is a specification.

The invention relates to ties for upholstery springs, and has for its object to provide a device of this character which may be easily and quickly applied to adjacent springs for effectively securing the springs together and at the same time flex with the springs when weight is applied thereon. Also to provide a tie of this character which will eliminate the use of a separate or independent means for securing the tie to the springs.

20 A further object is to provide a tie for upholstery springs comprising an elongated strip of metal having spaced U-shaped bends adapted to receive opposite sides of convolutions of the springs, and to be securely 25 clamped on the convolutions by a tool after the tie has been placed in position. The U-shaped bends grip the convolutions and prevent lateral displacement of the springs in relation to the tie.

30 A further object is to provide an upholstery spring tie formed from a single piece of material provided with portions adapted to grip the convolutions of the springs thereby obviating the use of other securing 35 means for the tie, and at the same time reducing the cost of assembling the springs to a minimum and allowing the tie to be applied by unskilled labor.

With the above and other objects in view 40 the invention resides in the combination and arrangement of parts as hereinafter set forth, shown in the drawings, described and claimed, it being understood that changes in the precise embodiment of the invention 45 may be made within the scope of what is claimed without departing from the spirit of the invention.

In the drawing:—

50 Figure 1 is a side elevation of adjacent upholstery springs showing the tie applied thereto.

Figure 2 is a horizontal sectional view taken on line 2—2 of Figure 1.

55 Figure 3 is a detail perspective view of a portion of the tie.

Referring to the drawing the numeral 1

designates adjacent upholstery springs of conventional form, which upholstery springs are equally spaced from each other and may be of any number desired according to the type of furniture on which the springs are used. It is now the practice to provide ties wherein separate means, for instance wire, is used to secure the ties to the convolutions 2 of the springs. To obviate 60 this difficulty the ties 3 are provided, which ties are formed from elongated strips of sheet metal which extend across the convolutions 2, and are provided with U-shaped bends 4 spaced apart according to the diameter of the convolutions 2 and the spacing 65 between the springs 1, whereby when the opposite sides of the convolutions 2 are disposed in the U-shaped bends 4, the springs will be in normal spaced relation to 70 each other. After the convolutions 2 have been placed in the bends 4, a clamping tool is applied to the bends 4 adjacent their inner ends, and the U-shaped bends securely 75 clamped on the convolutions 2, thereby positively securing the convolutions 2 and the 80 springs in spaced relation to each other. It will be noted that during the clamping operation, owing to the width of the ties and its grip on the convolutions 2 lateral displacement or movement of the ties is 85 prevented as such movement can occur only by the tie turning as a whole on a center coincident with the center of the springs, which turning movement cannot occur because of 90 the connection of the tie with other springs. The ties 3 have sufficient flexibility to give 95 with the springs when weight is applied thereto, but sufficiently rigid to prevent opening of the clamped U-shaped portions 4 when weight is applied on the springs.

From the above it will be seen that an upholstery spring tie is provided, which will positively hold the springs tied together and that the tie will not become laterally displaced on the convolutions 2. It will also be seen that the use of other means, such for instance as twisted wire to secure the ties to the convolutions 2 is obviated and that the ties may be quickly applied 100 by unskilled labor and at a minimum cost.

The invention having been set forth what is claimed as new and useful is:—

1. The combination with adjacent end convolutions of adjacent upholstery springs, 110 of a tie for said springs, said tie comprising an elongated metallic strip extending across

the end convolutions, said metallic strip being provided with offset bends in which the opposite sides of the convolutions are received and clamped, said offset bends forming means whereby the strip is secured to the convolutions and the strip outwardly spaced from the convolutions.

2. The combination with adjacent end convolutions of adjacent upholstery springs, of a tie for said springs, said tie comprising an elongated metallic strip extending across the convolutions, said strip being pro-

vided with U-shaped bends for the reception of opposite sides of the convolutions, said bends forming means whereby upon a clamping action being applied to the opposite sides thereof the convolutions may be securely clamped to the tie and the strip outwardly spaced from the convolutions a substantial distance.

In testimony whereof I affix my signature.

THEODORE HAUSER.
